SELF-STARTER FOR INTERNAL-COMBUSTION ENGINES.

1,117,739.

Specification of Letters Patent.

Patented Nov. 17, 1914.

Application filed December 17, 1913. Serial No. 807,266.

To all whom it may concern:

Be it known that we, ALEXANDER WINTON and HAROLD B. ANDERSON, citizens of the United States, residing at Cleveland, in the county of Cuyahoga and State of Ohio, have invented certain new and useful Improvements in Self-Starters for Internal-Combustion Engines, of which the following is a specification, reference being had therein to the accompanying drawing.

This invention relates to improvements in self starters for internal combustion engines and appertains to a self starter in which air under compression is utilized to initially turn the engine over until it picks up under its own power.

The particular kind of self starter here disclosed is one in which the means for furnishing the air under pressure is operated by the engine and stored in a tank, from which it is released under pressure and admitted to suitable means for giving the engine a starting movement to enable it to pick up under its own explosive power.

The primary object of the present invention is to provide means for putting into operation the air compressing mechanism simultaneously or substantially simultaneously with the imparting to the engine of the starting movements through the releasing of the compressed air from the storage tank, whereby all damage to any part of the compressing mechanism the connecting mechanism or the engine is avoided, which is liable to happen to either one or both of said mechanisms if the compressing device is thrown into operation after the engine is running under its own power and therefore at a high speed relative to its starting speed.

Another object of the present invention is to provide an automatic mechanism for holding the compressing mechanism in operative connection with the engine after set in motion until the tank is charged to a predetermined pressure and to be then automatically thrown out of operative connection with the engine.

A further object of the present invention is to cause the simultaneous or substantially simultaneous connection of the compressing mechanism with the engine during its starting movement and to automatically hold the compressing mechanism in operation until the desired predetermined pressure is stored

in the storage tank and then the compressing mechanism automatically thrown out of operation with the engine, whereby all injury to the parts is avoided when they are thrown into operative relation and over-storage of pressure in the tank and thereby injury to the tank or the system prevented.

A further object of the present invention is to provide means whereby a single manual movement will cause the release of the stored pressure from the tank to the means for turning over the engine and the coupling up of the air compressing device with the engine; the said compressing device being automatically held in operation until the proper pressure is stored and then automatically thrown out of operation with the engine, thus requiring only a single movement of the operator to start the engine, the maintenance of the proper storage in the tank being taken care of automatically and without any attention on the part of the operator.

Referring now to the accompanying drawings: Figure 1 is a side elevation showing diagrammatically the parts embodying the invention, the automatic feature being shown in section in said diagrammatic illustration; Fig. 2 is a longitudinal sectional view of the manually operated valve for releasing the compressed air from the tank into the starting mechanism; Fig. 3 is an enlarged view of the clutch or connecting device between the engine and the compressor and the automatic device for holding the clutch in and out of operative relation to the compressor, the parts being shown in released positions; Fig. 4 is a view similar to Fig. 3 but showing the clutch and the automatic parts in position to operatively connect the engine and the compressor; Fig. 5 is a diagrammatic view, partially in section, similar to Fig. 1, but showing a slightly modified construction; Fig. 6 is an enlarged perspective view showing the foot operated bell crank lever in this modified construction; Fig. 7 is a side elevation showing diagrammatically the parts comprising this invention, the automatic feature being shown in section, and a modification in the means for imparting to the engine a starting movement. Figs. 8, 9 and 10 are detailed views of the distributing valve used in Figs. 1 and 2.

Referring now to the drawings in which

like reference numerals indicate the same parts in the several views 1 is an engine which is here shown as of the six cylinder type. 2 is a suitable air compressor, preferably located at the front end of the engine as here shown, though the location of this device in respect to the engine is not essential to the invention, but the position shown is considered the most convenient for coupling it up with the engine. A suitable clutch 3 is located between the compressor 2 and a shaft 4 that is operatively connected with the engine. Preferably this shaft 4 is the cam shaft of the engine though it may be any other suitable movable member or shaft operatively connected with the engine. The type of clutch here shown as illustrated in Figs. 3 and 4 is of the positive type, although the type of clutch also is not essential to the embodiment of the inventive idea. This clutch as here illustrated comprises a movable member 5 which is keyed to but slidably on the shaft 4 and is provided with a tongue 6 adapted to enter a groove 7 on 25 the co-operating clutch member operatively connected with the compressor 2.

A suitable storage tank 7' is provided and is preferably so located in respect to the car body that it is not visible, although the location of the tank is not essential to the present invention. Pipes 8 and 10 connect the compressor 2 with the tank 7' and the pipe 8 is an inlet pipe to the tank 7 and an outlet pipe 10 is connected with the tank 35 and this pipe extends up to a suitable point where (in the construction shown in Fig. 1), the operative member or stem 11 of a manually operated releasing valve 12 will extend through the dash 13 of the car, where 40 it can be pushed outward by either the hand or the foot against a suitable head 14.

The type of manually operated releasing valve is shown enlarged and in section in Fig. 2. The valve is normally held seated by a suitable spring 15' and is unseated by a pressure against the head or member 14. As shown the valve is located in a suitable valve casing 15 to which the inlet pipe 10 is connected at one side of the valve 12 and 50 to which an outlet pipe 16 is connected at the opposite side of the valve 12. A distributing valve casing 17 is operatively connected with the engine and with the valve shaft, and the valve (not shown) is provided with a plurality of openings corresponding with the six cylinders and is adapted to alternately register with the pipes 18 that connect with the respective cylinders, and this communication is made 55 with the said pipes 18 of the respective cylinders in their firing order and during the explosion stroke. In this way when the releasing valve 12 is opened the compressed air or other analogous compressed fluid is

released from the tank in the form here shown, it enters directly the cylinders of the engine and in this way the pistons are directly caused to give the engine its initial starting movement. It is preferred to have the air act directly on the engine as here shown, rather than through a separate air actuating mechanism, though the present invention is not limited to any particular air actuated devices for imparting to the engine the initial starting movement, since the invention is applicable to other methods of utilizing the compressed air for imparting the initial movements to the engine.

Returning now to the mechanism for connecting the compressor 2 with the engine, a rod 19 carries at its forward end a yoke 20 that engages the slideable clutch member 5 to move it in and out of operative connection with the compressor and the opposite end of the rod 19 carries a piston 21 which is located within a cylinder 22 and a pipe 23 connects the opposite end of the cylinder with the pipe 16 so that when air is released by the valve 12 it enters the cylinder 22 at the same time it enters the distributing valve 90 casing 17 and forces the rod 19 forward, carrying the clutch member 5 into engagement with the clutch member of the compressor 2, thus connecting the engine and the compressor. It will thus be seen that the admission of air to the starting mechanism of the engine simultaneously or substantially simultaneously admits air to the cylinder 22 and connects the compressor with the engine while the engine is being rotated through the medium of the compressed air and is therefore rotating slowly. By connecting the compressor with the engine at the time it is given its initial starting movement, there is no shock to the compressor or to the engine in making the connection and therefore injury to the parts is avoided.

As long as the valve 12 is held open the clutch 5 connects the compressor with the engine and the compressor is working and storing the tank 7'. When the engine starts under its own power the manually operated member 14' is released and the valve 12 closed, thus cutting off the air communication between the tank 7' and the cylinder 22. To prevent the clutch from being released when the valve 12 is closed, we provide a mechanism that automatically holds it in operative relation to the compressor until the pressure in the tank 7' has reached the desired and predetermined degree. This mechanism in the form here shown as one of the expressions of the inventive idea comprises a toggle lever device having two toggle arms 24 and 25. These toggle levers have their inner ends pivotally connected at 26, while the outer end of the lever 24 is pivotally connected at 25' to a casting or

casing of the cylinder 22 and the outer end of the toggle lever 25 is pivotally connected at 26' to one end of an arm 27, the other end of the arm being firmly connected to the rod 5 or stem 19 of the piston 21.

A cylinder 28 is located adjacent the cylinder 22 and is preferably formed in the same casting with the last mentioned cylinder. Located within this cylinder 28 is a 10 piston 29 and this piston carries at its outer end a valve 30 which controls an inlet opening 31 to the said cylinder. This inlet opening 31 is in communication with the tank 7' through the medium of a pipe 32. A suitable spring 33 normally holds the piston 29 in position so that the valve 30 closes the inlet opening 31 and the tension of this spring 33 is regulated by an adjustable screw member 34 by means of which the spring can be 15 compressed or released. In this way the valve 30 becomes a safety or pop valve which open when the pressure in the tank 7' has reached the pressure determined by the tension of the spring 33. When the valve 30 is unseated by this pressure air is admitted 20 to the cylinder 28 and the piston 29 is moved backward in the cylinder 28 against the tension of the spring. The backward movement of the piston 29 causes its cone-shaped 25 portion 35 to engage an adjustable screw 36 carried by the toggle arm 24 and move the toggle arm upward and the pivotal point 26 above a horizontal line between the points 25' and 26', and the toggle arms will then 30 assume the position shown in Fig. 3. With the toggle arms in the position shown in Fig. 1 the axis of the pivotal point 26 is slightly 35 below a horizontal line between the axes of the pivotal points 25' and 26' and in this 40 position the rod 19 and the clutch 5 are held in position to operatively connect the compressor 2 and the engine 1. An adjustable screw 37 serves to regulate the limit of downward movement of the toggle arms and a 45 weight 38 serves to assist in moving them downward when the piston 21 and the rod 19 are moved outward by the pressure from the tank 7' as before described.

The parts of the mechanism are normally 50 in the positions shown in Fig. 3, that is, with the clutch out of operative connection with the compressor 2 and the toggle arms in their upward position. By opening the valve 12 through manual pressure on the 55 member 14, air or other suitable pressure is admitted substantially simultaneously to the engine cylinders through the valve casing 17 and the distributing valve therein and to the cylinder 22. By reason of this fact the 60 clutch 5 is moved into operative connection with the compressor substantially simultaneously with the movement of the engine by the movement outward of the piston 21 and its rod 19. As soon as the engine starts un-

der its own power the valve 12 is closed by 65 releasing the member 14', but the clutch is automatically held in operative connection with the compressor 2 by reason of the position of the toggle levers 24 and 25 shown in Fig. 1, the outward movement of the piston 70 21 and rod 19 having caused these members to assume that position, and they remain in that position until the compressor 2 has created in the tank 7' the desired and pre-determined pressure. When this has been 75 reached the pop or safety valve 30 is opened automatically by the pressure forcing the piston 29 inward and by its cone-shaped portion 35 and the engaging screw or member 80 36 of the toggle levers, kicks the toggle levers upward. At this time the valve 12 as stated is closed and there is a suction caused on the piston 21 through the pipes 18, 16 and 23 and this suction draws the piston to the outer end of the cylinder 22 and 85 will hold the toggle levers in the released position shown in Fig. 3. If desired, the return movement of the rod 19 and piston 21 may be assisted when the toggle levers are 90 kicked upward as described, by means of a spring 39 located between a suitable stationary bushing 40 and a collar 41 on the said rod, a collar 42 serving to limit the movement of the rod 19 either under the tension of the spring 39 or the suction action on the 95 piston 21, or both. In this manner the parts are held in the position shown in Fig. 3 until the engine is again started. When the engine is again started the operation just described will be repeated and the tank 7 will 100 always be kept charged with the proper amount of pressure to insure the starting of the engine under the most severe conditions.

By means of this construction the starting of the engine automatically causes the charging of the tank 7' and therefore maintains the predetermined pressure in the tank automatically and always insuring the starting of the engine. It will be observed that in this respect this mechanism in its automatic action is similar to the electric starters now in use on the market and well known to those skilled in the art, in which electric starters the starting of the engine throws in the generator for charging the storage 115 battery and this is true of the system here described in that the starting of the engine automatically causes the charging of the tank to the predetermined pressure when the charging device is automatically kicked out 120 of operation. The system herein described obviates the necessity of carrying a heavy storage battery and the complicated electrical system which is very difficult to understand and difficult and usually impossible of 125 repair by the ordinary operator and especially on the road, and these facts are well recognized by those who are acquainted with

the electrical starting systems. On the other hand, the system here disclosed is mechanical only and its failure to operate can be readily observed by any ordinary mechanic and its trouble located.

5 A suitable pressure gage 43 is provided in the system so that the operator can always see the pressure in the tank and should a leak occur in the system and the pressure fall, it is only necessary for the operator to slow down his engine and open the valve 12, when the automatic operation hereinbefore mentioned will take place and the tank be charged to the predetermined amount 10 when the pressure device would be automatically thrown out, as before described.

In the modification shown in Fig. 5 the operation already described is reversed in this, that a foot treadle is provided for 20 throwing in the clutch and simultaneously with the throwing in of the clutch the air is admitted from the storage tank to the starting system, thus accomplishing the simultaneous or substantially simultaneous 25 connection between the engine and the compressor at the time the engine is started. In all other respects the operation of Fig. 5 is the same as that described of Figs. 1, 2, 3 and 4 and like reference letters are 30 applied to Fig. 5 to the parts which are duplicates of those in Figs. 1, 2, 3 and 4. We will now describe those features of Fig. 5 which differ from Fig. 2.

A foot actuated lever *a* is provided within 35 reach of the operator and as here shown this lever is of the bell crank type and carries a foot button or pedal *b* at one end, the other end being connected to a link or rod *c* and the upper end of this link or rod *c* is connected with one end of a bell crank lever *d*, the other end of the last mentioned bell 40 crank lever engaging a collar *e* on the stem of the valve 12. A second bell crank lever *f* is intermediately pivoted to a suitable support *g* and one end of this bell crank lever is connected to a link or rod *h*, the other 45 end of the rod *h* having a vertical slot *i* through which a pin *l* of the bell crank lever *d* passes. The other end of the bell crank 50 lever *f* is connected with the rod 19 by a pin and slot connection 20'.

The operation of this device is as follows: By pushing downward on the foot button or pedal *b* the bell crank lever *f*, link *h*, the 55 clutch and the automatic mechanism for holding the clutch in operation with the compressor 2 are carried into the position shown in Fig. 5, and at the same time the valve 12 is unseated and air is admitted to 60 the pressure starting mechanism in the same way described in connection with Fig. 1. As soon as the engine starts the foot button or treadle *b* is released and it, together with the valve 12 and the valve stem, returns to 65 the position shown in Fig. 5 without dis-

turbing the position of the clutch and its automatic mechanism. As soon as the pressure in the tank 7' has reached the predetermined degree the locking toggle parts are kicked out of locking position as before described and the clutch is released and this will draw down on the link or rod *h* and place it in position in respect to the bell crank lever *d* for a repeated operation when it is desired to again start the engine. It 70 will be observed that in Fig. 5 the pipe 23 of Fig. 1 is omitted and the cylinder 22 and piston rod 21 may also be omitted without affecting the operation of this modified form, provided some other guide is furnished for 75 the end of the rod 19 to which the arm 27 is connected for the purpose of insuring the straight movement of the rod. The function of the cylinder 22 and piston 21 in Fig. 5 is only to guide the rod 19 and in 80 this instance the spring 39 serves to hold the clutch in the position shown in Fig. 3 and therefore out of operative position.

We desire it to be understood that the constructions herein shown and described are 85 only intended as mechanical expressions of the broad inventive idea and that they may be varied without departing from the spirit and scope of the generic invention herein disclosed.

95 A shut-off valve *B* is provided by means of which the line 10 can be closed at night or throughout the system. When the mechanism is in normal operation, this valve *B* is open. This valve *B* will be placed conveniently to be operated through the vehicle dash. With the parts in the position shown 100 in Fig. 7 the clutch 5 can be thrown to disconnect the pump 2 before the pre-determined pressure is reached in the tank 7' by closing the valve *B*, should it be desired to have the mechanism so operated. In this instance the pump 2 will raise the pressure 105 quickly to the maximum pressure necessary to cause the valve 29 unseat and be forced end-wise and cause the toggle levers to move upward in the manner before described and disconnect the pump 2. In the arrangement shown in Fig. 7 an air engine *A* is used to give the engine 1 a starting movement. A gear wheel *n* of this air-engine meshes with the gear *m* of the engine fly wheel. When 110 the air pressure is admitted to the engine *A* through the pipe 16' by opening the valve 15' the air-engine is caused to operate and in turn operate the engine 1. In all other respects the mechanism operates as to its automatic features the same as in the other constructions herein shown.

Having thus described the invention what is desired to be secured by Letters Patent is:

1. A starting device for internal combust- 130

tion engines, comprising a pressure producing device, a storage tank in communication with said device, an engine starting mechanism utilizing the stored pressure in the tank, means operatively connecting the pressure producing device with the engine approximately simultaneously with the starting movement of the engine and means for disconnecting the pressure producing device from the engine when a predetermined pressure is reached in the said storage tank.

2. The combination with an internal combustion engine, of a pressure producing device normally disconnected with the engine, a storage tank in communication with said device, a starting mechanism utilizing the pressure from the tank for imparting a starting movement to the engine, means operatively connecting the pressure producing device with the engine and the pressure of the tank with the starting mechanism approximately simultaneously, and means controlled by the pressure in the tank for disconnecting the pressure producing device from the engine.

3. The combination with an internal combustion engine, of a pressure producing device normally disconnected from the engine, a pressure storage tank in communication with said device, a starting mechanism for the engine utilizing the stored pressure of the tank for imparting a starting movement to the engine, means for connecting the pressure in the tank with the starting mechanism, and means controlled by the pressure in the tank for operatively connecting and disconnecting the pressure producing device with the engine.

4. The combination with an internal combustion engine, of a pressure producing device normally disconnected with the engine, a pressure storage tank in communication with said device, a starting mechanism for the engine adapted to utilize the stored pressure of the tank for imparting a starting movement to the engine, manually operative means for connecting the pressure in the tank with the starting mechanism, and means controlled by the pressure in the tank for connecting and disconnecting the pressure producing device with the engine.

5. The combination with an internal combustion engine, of a pressure producing device normally disconnected with the engine, a pressure storage tank in communication with said device, a starting mechanism for the engine utilizing the stored pressure of the tank for imparting a starting movement to the engine, mechanism operated by the pressure in the tank for connecting and disconnecting the pressure producing device with the engine, a manually operated means adapted to connect the last said mechanism with the pressure in the tank and the pres-

sure in the tank with the starting mechanism.

6. The combination with an internal combustion engine, of a pressure producing device normally disconnected with the engine, a pressure storage tank in communication with said device, a starting mechanism adapted to utilize the pressure of the tank for imparting a starting movement to the engine, means operated by the pressure in the tank for connecting the pressure producing device with the engine, means controlled by the pressure in the tank and continuing the connection until the pre-determined pressure in the tank is obtained and the pressure then causing the release of the holding means and the disconnecting of the pressure device from the engine.

7. The combination with an internal combustion engine, of a pressure producing device normally out of operative communication with the engine, a pressure storage tank in communication with said device, a starting mechanism adapted to utilize the stored pressure of the tank for imparting a starting movement to the engine, manually operated means for connecting the pressure in the tank with the starting mechanism means for connecting the pressure device with the engine and controlled by said manually operated means, a locking mechanism for holding the pressure producing device in operative connection with the engine, a pressure actuated device in connection with the tank and releasing the locking mechanism and disconnecting the pressure actuated device from the engine when the pressure in the tank has reached a pre-determined degree.

8. The combination with an internal combustion engine, of a pressure producing device normally disconnected with the engine, a pressure storage tank in connection with the device, a starting mechanism adapted to utilize the pressure of the tank for imparting a starting movement to the engine, means actuated by the pressure in the tank for connecting the pressure producing device to the engine and connecting the pressure of the tank with the starting mechanism, and a locking mechanism for the connecting device comprising toggle levers, and a pressure actuating the member in connection with the tank and through the said toggle levers to an unlocking position when the pressure in the tank has reached a pre-determined degree.

9. The combination with an internal combustion engine, of a pressure producing device normally disconnected with the engine, a pressure storage tank in connection with said device, a starting mechanism adapted to utilize the pressure in the tank for imparting a starting movement to the engine, means actuated by the pressure in the tank

for connecting the pressure producing device with the engine, a manually operated means adapted to connect the pressure in the tank with the connecting means and with the starting mechanism, a toggle lever connected with the means for connecting the pressure producing device with the engine, a cylinder having connection with the tank, a valve in the cylinder yieldingly holding the opening closed, the valve having a cam-shaped portion and the toggle lever having a projection to engage said cam whereby when the pressure in the tank has reached a

pre-determined degree the valve is unseated causing the cam to move the toggle levers to 15 releasing position and permitting the disconnecting of the pressure producing device with the engine.

In testimony whereof we hereunto affix our signatures in the presence of two witnesses. 20
